Primary Examiner — Susan Moon Lee(74) *Attorney, Agent, or Firm* — Polster, Lieder, Woodruff & Lucchesi, L.C.(57) **CLAIM**

I claim the ornamental design for an RFID tag reader housing, as shown and described.

DESCRIPTION

FIG. 1 is a top perspective view of the RFID tag reader housing;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines are included for the purpose of illustrating environmental structure and form no part of the claimed design.
